Design No. 3,593, dated August 3, 1869.

DESIGN FOR A TRADE-MARK.

The Schedule referred to in these Letters Patent and making part of the same.

To all whom it may concern:

Be it known that I, HENRY ASBURY, of Philadelphia, county of Philadelphia, State of Pennsylvania, have originated a new Design for a Trade-Mark; and I do hereby declare that the accompanying drawing, and following explanation thereof, form a full, clear, and exact description of the said design.

In the drawing, the figure represents my design for a trade-mark, to be applied to measuring-faucets, the said design consisting of the figure A, of the peculiar form illustrated in the drawing.

Within this figure are the numerals shown, and graduated marks *a* are arranged in a circle, at the

centre of which is the figure, *b*, of a keystone, and the pointer *d*.

I claim the design for a trade-mark, substantially as described, and as illustrated in and by the accompanying drawing.

In testimony whereof, I have signed my name to this specification, in the presence of two subscribing witnesses.

HENRY ASBURY.
